UNITED STATES PATENT OFFICE.

JOSEPH ARKINS, OF CHICAGO, ILLINOIS, ASSIGNOR OF ONE-HALF TO E. F. SLOCUM, OF SAME PLACE.

VELOCIPED.

SPECIFICATION forming part of Letters Patent No. 235,399, dated December 14, 1880.

Application filed May 20, 1880. (No model.)

To all whom it may concern:

Be it known that I, JOSEPH ARKINS, a citizen of the United States, residing at Chicago, in the county of Cook and State of Illinois, have invented a new and useful Improvement in Velocipedes, of which the following is a specification.

The object of my invention is to provide an improved vehicle to be propelled by the passenger, which may be used by persons of either sex, and be adjustable to suit either adults or children, the novelty of which consists in a new combination of known parts with a useful peculiarity (with reference to each other and to the space they occupy) of levers or arms for propulsion and their capacity of adjustment, the several parts of which are set forth and described as follows:

Figure 1 represents a side elevation of a tricycle, showing the general construction of the parts and their relation to each other. Fig. 2 is an enlarged view of the parts E, D, and M.

In the drawings, A represents a driving-wheel, (there being two,) rigid with the hinder axle; B, single smaller forward wheel, set in a swivel-bearing and controlled by guiding-lever C; D D, propelling-levers, overlapping each other about one-third their length, in this device, to be operated by the feet.

E is an S-shaped bearing attached by a collar-bolt to the slotted rest M. The peculiar construction of this bearing, as shown in Fig. 2, permits an addition to the effective length of the levers without conflicting with each

other, and causes a proportional diminution of 35 the curvature of their sweep.

M is a slotted rest, to which bearing E is attached by a collar-bolt, admitting changes of adjustment in the length of the connections to suit the passenger; F, take-up wheel, loose 40 on the axle, and engaging through pawl G with ratchet I, which is keyed to the axle; H, spring for returning take-up wheel to position after pressure is removed from the lever.

L is a cord, attached to lever D and take-up wheel F, connecting the propelling parts, through which forward motion is given.

The levers D D are connected at their outer ends with two take-up wheels, F, on the axle, by means of two cords, L, as above described, 50 and the passenger, taking position upon the seat, with one foot upon each lever, by imparting reciprocating motion to the same propels the vehicle.

I am aware that the tricycle propelled by 55 foot-levers is not new. I therefore do not claim such a combination, broadly; but

What I do claim as my invention, and desire to secure by Letters Patent, is—

In a velocipede, the slotted rest M, S-shaped 60 bearing E, adjustable thereon, and levers D, in combination with cords L and take-up mechanism, all constructed and operated substantially as described.

JOSEPH ARKINS.
